FIG. 1

FIG. 2

FIG. 3

FIG. 4

FIGURE 1 is a perspective view from directly in front of and slightly above my message center cabinet,

FIGURE 2 is a perspective view showing the front, left side and top of my message center cabinet, with the front doors open and the hinged top leaf in its unfolded position,

FIGURE 3 is a perspective view showing the rear, left side and top of my message center cabinet, and

FIGURE 4 is an elevational view of the right side of the cabinet with the hinged upper panel folded down.

The dominant features of my design reside in the portions shown in full lines in the drawings.

I claim:

The ornamental design for a message center cabinet, substantially as shown and described.
